UNITED STATES PATENT OFFICE

WILLIAM J. ANDRES, OF SOUTH BEND, INDIANA, ASSIGNOR, BY MESNE ASSIGNMENTS, TO BENDIX AVIATION CORPORATION, OF NEW YORK, N. Y., A CORPORATION OF DELAWARE

DRUM-GRINDING MACHINE

Application filed March 18, 1929. Serial No. 348,097.

This invention relates to machines for grinding or otherwise treating brake drums or the like, and is illustrated as embodied in a novel compact and inexpensive machine 5 for truing up brake drums by a grinding operation without necessarily removing them from their wheels. An object of the invention is to provide means for traversing the work under power past the operating 10 tool, without complicating the machine and preferably in such a manner as to leave the machine extremely compact so that it will not take up much floor or bench space in a garage or service station. I prefer to use 15 individual motor drives on this machine, and the illustrated embodiments show electric motors built into the machines.

These illustrated machines are arranged 20 each with its motor mounted on a suitable base, the armature shaft having a high speed tool at one end and being connected at its other end by means such as novel reduction gearing to a low-speed shaft on which the 25 wheel and drum are mounted. Thus a single motor drives the work slowly past a rapidly-driven tool. An important minor feature relates to a novel adjustable support such as an eccentric bearing for the low-speed shaft, permitting relative bodily adjustment between the work and the tool.

The above and other objects and features 30 of the invention, including various novel and desirable details of construction, will be apparent from the following description of the 35 illustrative embodiments shown in the accompanying drawings, in which:

Figure 1 is a top plan view of a machine comprising an embodiment of the invention;

Figure 2 is a side elevation of this 40 machine;

Figure 3 is a section on the line 3-3 of Figure 1, showing the reduction gearing connecting the two shafts;

Figure 4 is a partial section on the line 45 4-4 of Figure 1, showing one means for turning the eccentric bearing for the low-speed shaft;

Figure 5 is a partial section on the line 50 5-5 of Figure 1, showing one means for clamping the adjusted eccentric bearings;

Figure 6 is a top plan view of another machine comprising a second embodiment of the invention;

Figure 7 is a section on the line 7-7 of 55 Figure 6, showing the novel reduction gearing, and showing the motor, etc., in elevation;

Figure 8 is a partial section on the line 8-8 of Figure 6, showing the means for turning the eccentric shaft bearing in this 60 machine; and

Figure 9 is a partial section on the line 9-9 of Figure 6, showing the means for clamping the eccentric bearing.

The machine of Figures 1-5 includes a 65 suitable base 10, which may be mounted on a bench or a pedestal, and on which is mounted an electric motor 12 having an armature shaft 14 rotating, for example, at 4,000 R. P. M., and having at its 70 front end a tool such as a grinding wheel 16 of emery or the like. The rear end of the armature shaft has a worm meshing with a worm gear 18 on one end of a transverse shaft 20 having at its opposite end a worm 75 driving a worm gear 22 on a low-speed shaft 24 rotating, for example, at 5 or 10 R. P. M. Gearing 18-22 forms reduction gearing connecting the rear ends of the two shafts 14 and 24, the gearing being arranged in a 80 suitable housing 26.

The front end of shaft 24 is adjacent the 85 tool 16, and forms a power-driven rotatable support engaging the hub of a wheel 28 having a brake drum 30 which is to be trued up by tool 16. A support such as a roller 32 on a swinging link 34 connected to the base 10, and urged toward tool 16 by a spring 36, may, if desired, be arranged to engage the 90 drum 30 or an equivalent piece of work opposite the tool 16. It will be seen that shaft 24 slowly traverses the work past the rapidly revolving grinding wheel 16.

In order to provide for adjusting the 95 work bodily toward and from the tool 16, I prefer to mount the shaft 24 eccentrically in a long bearing member 38 having at its front end a cylindrical portion 40 journaled in a post 42 rising from the base 10 and having at its rear end a cylindrical portion 100

44 journaled in a similar post 46, the two end portions (in which the shaft 24 is eccentrically journaled) being rigidly connected by a U-shaped section strengthened by a 5 longitudinal rib 48 as best shown in dotted lines in Figure 4.

As appears in Figures 1 and 4, part 44 of bearing 38 is provided with a handle 50 by which it may be turned to make the desired 10 adjustment, while as shown in Figures 1 and 5, the bearing may be clamped frictionally to preserve the adjustment by a shoe 52 operated by a threaded stem 54 having an external operating handle 56.

15 The machine of Figures 6-9 differs from the one just described principally in being arranged to use a conical grinding wheel 116, arranged at such an angle that its work-engaging face is substantially parallel to 20 shaft 24, thus inclining the head of the tool backwardly so that it will clear the heads of attaching bolts, etc., in the head of the brake drum 30. This puts the motor 12 at a slight angle, so that shafts 14 and 24, while generally parallel, are not exactly so as in the 25 first embodiment, the reduction gearing permitting this arrangement without difficulty.

In this case, also, bearing 38 is turned to 30 adjust shaft 24 by means of a worm 60 carried by post 42 and operated by an external hand wheel 62, and meshing with a worm gear cut in the periphery of part 40 of the bearing. The clamping of the bearing is done by a nut 64 having an external operating 35 handle 66 and threaded on a spindle 68.

The tool 116 may be dressed when necessary by a suitable tool 70, of any desired and usual type, threaded for lengthwise adjustment in the end of a slide 72 mounted on 40 base 10 and operable manually by a suitable handle 74. A stop 76 determines the idle position of the slide. By moving tool 70 back and forth while the tool 116 is rotating, the surface of the latter is trued up. 45 The tool 70 moves substantially along the line at which the work 30 is tangent to the grinding wheel 116 when the latter is in use. The tool 16 of the first machine may be trued in a similar manner by a tool (not 50 shown) threaded into the head 76 of a slide 78 operated by a handle 80.

It should be noted that bearing 38 is preferably so arranged as to swing shaft 24 in an arc directly toward and from the point of 55 tangency of tool 16 or 116 and the work, so that there is substantially no shifting of the work crosswise of the tool.

While two illustrative embodiments have been described in detail, it is not my intention to limit the scope of the invention to those particular embodiments, or otherwise than by the terms of the appended claims.

I claim:

1. A machine for truing brake drums or 65 the like comprising, in combination, a motor

with a high-speed armature shaft having a tool at one end, reduction gearing at the other end of the armature shaft, and a shaft generally paralleling the armature shaft and driven at one end by said gearing and having at its other end a work support adapted to traverse the work past said tool, together with an angularly adjustable eccentric bearing for said second shaft operable to adjust the work bodily with respect to the tool. 70

2. A machine for truing brake drums or the like comprising, in combination, a motor with a high-speed armature shaft having a tool at one end, reduction gearing at 75 the other end of the armature shaft, and a work support driven by said gearing and adapted to traverse the work past said tool, together with a roller yieldingly engaging and supporting the work opposite the tool. 80

3. A machine for truing brake drums or the like comprising, in combination, a motor with a high-speed armature shaft having a tool at one end, reduction gearing at the other end of the armature shaft, and a shaft generally paralleling the armature shaft and driven at one end by said gearing and having at its other end a work support adapted to traverse the work past said tool, together with an angularly adjustable eccentric bearing for said second shaft operable to adjust the work bodily with respect to the tool, and one device for turning the bearing and another for clamping it in adjusted position. 90

4. A machine comprising, in combination, a base, a motor mounted on said base and having an armature shaft with a tool at one end and a worm at its other end, a transverse shaft having at one end a worm gear driven by the armature shaft worm and having a driving worm at its other end, and a driven shaft generally paralleling the armature shaft and having at one end a worm gear driven by the driving worm and having at its other end a work support adjacent said tool. 100

5. A machine comprising, in combination, a motor having an armature shaft with a tool at one end and a worm at its other end, a transverse shaft having at one end a worm gear driven by the armature shaft worm and having a driving worm at its other end, and a driven shaft generally paralleling the armature shaft and having at one end a worm gear driven by the driving worm and having at its other end a work support adjacent said tool, together with an adjustable eccentric bearing for the driven shaft which can be turned to vary the relative positions of the work and the tool. 115

6. A machine comprising, in combination, a motor having an armature shaft with a tool at one end and a worm at its other end, a transverse shaft having at one end a worm gear driven by the armature shaft worm and

having a driving worm at its other end, and a driven shaft generally paralleling the armature shaft and having at one end a worm gear driven by the driving worm and having at its other end a work support adjacent said tool.

7. A machine comprising, in combination, a motor having an armature shaft with a tool at one end and a worm at its other end, a transverse shaft having at one end a worm gear driven by the armature shaft worm and having a driving worm at its other end, and a driven shaft generally paralleling the armature shaft and having at one end a worm gear driven by the driving worm and having at its other end a work support adjacent said tool.

8. A machine comprising a high speed shaft, a rotatable tool at one end of the shaft, reduction gearing at the other end of the shaft, a second shaft generally paralleling the first mentioned shaft and driven at one end by the reduction gearing, work supporting means formed at the other end of the second shaft, and an angularly adjustable eccentric bearing for the second shaft operable to adjust the work bodily with respect to the tool.

9. A machine comprising a high speed shaft, a tool at one end of the shaft, reduction gearing at the other end of the shaft, a second shaft driven by the reduction gearing and adapted to traverse the work past the tool, an angularly adjustable eccentric bearing for the second shaft operable to adjust the work bodily with respect to the tool, and means for clamping the second shaft in its adjusted position.

In testimony whereof, I have hereunto signed my name.

WILLIAM J. ANDRES.
